PENCIL-POINT SHARPENER

George D. Martin, Olympia, Wash.

Application October 21, 1940, Serial No. 362,114

6 Claims. (Cl. 120—91)

It is a comparatively simple matter to provide a sharp point, such as accountants, draftsmen, and the like desire, upon an ordinary wood-encased pencil point or "lead," for the reason that no harm occurs if the tip of the encasing wooden barrel is rubbed upon or by an abrasive, which is employed to put the fine tip upon the pencil point. Indeed, in sharpening the pencil part of the barrel or wooden case is necessarily cut away or worn away with an abrasive. It is scarcely feasible, however, thus to sharpen the point of a "lead" which is projected from the tip of a mechanical pencil, that is, a pencil wherein leads are advanced or held within a barrel of metal or the like, for it is not desirable to permit the abrasive to come into contact with the tip of the barrel, and yet it is scarcely feasible to sharpen the point itself, with known sharpeners, without contact of the abrasive with the tip of the barrel at the same time it contacts with the projecting point of "lead." Because of this difficulty of providing a fine point upon the "lead" of mechanical pencils, these "leads" have been made thin, so that they cannot wear to an extremely broad point, but even this is unsatisfactory, for the point cannot be made nor kept fine and sharp, and the thin "leads" are more easily broken than those which are thicker, and are more expensive to produce, in part because of their greater fragility.

It is a primary object of the present invention to provide a pencil point sharpener for use specifically with mechanical pencils, which will enable the quick and easy sharpening of the point of the "lead" by an abrasive without the possibility of injury to the tip of the pencil's barrel.

More specifically it is an object to provide such a pencil point sharpener for use with mechanical pencils, which is of such small size that it may be carried by the end of the pencil, and may in turn support an eraser such as is commonly used with some such pencils, to the end that the entire assembly of pencil and sharpener, and, if used, eraser also, may be of no materially greater size in any dimension than the normal pencil, and to the final end that the sharpener may be carried always by and be available for use with the pencil needed.

A further object, then, appears, namely, that the construction and arrangement of such a pencil point sharpener for such use be so small and simple that it will permit the accomplishment of the other objects already named.

An associated object is to provide such a pencil 55 13 in the external sleeve 1, or any equivalent

point sharpener which can at need be disassembled and repaired or other parts substituted, in particular one which permits the substitution for a worn out abrasive surface of a fresh abrasive surface.

5 The invention comprises the novel parts and arrangement thereof, as shown in the accompanying drawing, and as will be described in this specification, and those constructions which are novel will be pointed out in the appended claims.

Figure 1 is an axial section through the device, showing it in operative relationship to the point of a mechanical pencil.

15 Figure 2 is an end view of the sharpener. Figure 3 is an exploded view of the sharpener and associated parts, and of the pencil which carries it.

20 My invention has no concern with the structure of the mechanical pencil, nor with the means to support or feed the "lead" through it. Only the exterior of the barrel 5 of such a pencil is shown, together with its tapered tip 50 and, in Figure 5, its opposite end 51, which will be referred to later. From the tip 50 protrudes the pencil point 4. The problem is to provide a fine point upon the "lead" 4, such as is illustrated in Figure 1, and to avoid scratching or otherwise marking or marring the barrel's tip 50, and, of course, to do this in a device of sufficiently small compass that it may be associated with and carried by the pencil as a part thereof.

25 The sharpener comprises an external sleeve 1, which is conveniently formed so that it is open at both ends. One end may, if desired, be slightly flanged over, as indicated at 10, to contain an abrasive-coated sleeve 2. Such a sleeve may be made up of ordinary fine sandpaper or emery cloth, sufficiently stiff, and of a size to fit snugly within the end of the sleeve 1.

30 Disposed at this end of the sleeve 1, in a position to obstruct entrance thereto, is a guard 3. This guard is apertured, as by the slit 30 extending from its periphery inwardly in a generally radial direction, and this guard is supported for rotation coaxially of the sleeve 1. To this end it may be secured upon the end of a pivot pin 31, which in turn is pivoted within 35 a pivot bearing member 61, which may take the form of a reduced sleeve or extension upon an inner sleeve 6. The pivot pin 31 may be headed, as indicated at 30, with the head received within a chamber 60 of the sleeve 6. A slight dimple 40 13 in the external sleeve 1, or any equivalent

means, may serve to limit inward projection of the sleeve 6, if necessary. This sleeve 6 may be slit, as seen in Figure 3, so that by its resilience it will fit snugly and friction-tight within the external sleeve 1 at the end opposite the abrasive-coated interior surface at 2.

The parts are so proportioned that when thus assembled the guard 3 obstructs entrance to the one end of the sleeve 1, but it is bifurcated, and its slit 30 is of such width as to admit the "lead" 4, but to obstruct entrance of the larger enclosing tip 50 of the barrel, the end of which abuts the outer face of the guard 3, as is illustrated in Figure 1. The "lead" 4 may be projected to a greater or less degree from the barrel's tip 50. If but slightly projected the conical tip or point which it is given by rotation of the barrel 1 round about the lead is comparatively blunt. If the "lead" is projected more, the point which it is given is a longer, finer point. To point it, it is only necessary to rotate the sleeve 1 around the projecting end of the "lead," as has been indicated by the full and dash line positions of Figure 1, and this gives to the projected end of the "lead" as sharp or fine a point as may be desired. The guard, of course, rotates with the "lead," in effect, and at all times prevents entrance of any of the metal parts of the pencil's barrel into position where they might contact the abrasive-coated surface 2. The projection of the "lead" is in all cases insufficient that it is unduly stressed, and there is no appreciable tendency to break off the projecting portion of the "lead."

The interior sleeve 6 may take the form of a cup, disposed at and opening towards the end of the sleeve 1 which is opposite that wherein is received the abrasive ring 2, and in this cup 6 may be received an eraser 7, within its metal cup 70. Such an eraser is commonly used with such mechanical pencils, and the length of the pencil is increased but slightly by the interposition of the sharpening device. The latter in turn is received within or otherwise securely but removably supported by the open end 51 of the barrel 5. The latter may be slit to provide, by its resilience, a friction-tight cup or socket to receive the sleeve 1.

If any part of the sharpener fails to operate properly it is an extremely simple matter to disassemble it. If the abrasive ring is worn or unduly clogged it may readily be removed and cleaned or a new one substituted. The entire device is simple, compact, and is available at all times to sharpen the point of the "lead," so that the point may readily be kept as sharp as the user may desire.

What I claim as my invention is:

1. A pencil point sharpener for mechanical pencils comprising a sleeve of a diameter approximating that of the pencil's barrel, removably securable upon an end of such a pencil, having an internal abrasive coating at one end, a guard disposed and formed to obstruct access to such end of the sleeve, and means for supporting said guard for rotation coaxially with the sleeve, said guard being apertured for projection of a pencil point within the sleeve and into contact with the abrasive coating therein, but the aperture being sufficiently small to engage and block such entrance and contact of the tip of the pencil's barrel.

2. A pencil point sharpener for mechanical

pencils comprising a removable sleeve for securement upon an end of such a pencil, having an abrasive coated inner surface at one end, a guard disposed transversely of and at the entrance to said abrasive coated end, and means supporting said guard for rotation coaxially within said sleeve, said guard being bifurcated from its periphery inwardly to define a generally radially disposed slit of a width to receive the pencil point and to enable it to engage the abrasive coated surface, but to block entrance of the tip of the pencil's barrel.

3. A pencil point sharpener for mechanical pencils comprising a sleeve open at both ends, a bifurcated guard having a slit only wide enough to pass the pencil point, but not the tip of the pencil's barrel, disposed to obstruct the entrance to one end of the sleeve, an abrasive coating within this end of the sleeve, a pivot pin spaced from and coaxial with the sleeve and supporting said guard, and extending thence towards the opposite end of the sleeve, and a pivot bearing member supporting said pin for rotation and preventing its relative endwise movement, said bearing member being received within and supported by the opposite end of the sleeve.

4. A pencil point sharpener for mechanical pencils comprising a sleeve open at both ends, a bifurcated guard having a slit only wide enough to pass the pencil point, but not the tip of the pencil's barrel, disposed to obstruct the entrance to one end of the sleeve, an abrasive coating within this end of the sleeve, a pivot pin spaced from and coaxial with the sleeve and supporting said guard, and extending thence towards the opposite end of the sleeve, a pivot bearing member supporting said pin for rotation and preventing its relative endwise movement, and an internal sleeve tightly received within the opposite end of the first sleeve, and supporting the pivot bearing member.

5. A pencil point sharpener for mechanical pencils comprising a sleeve open at both ends, a bifurcated guard having a slit only wide enough to pass the pencil point, but not the tip of the pencil's barrel, disposed to obstruct the entrance to one end of the sleeve, an abrasive coating within this end of the sleeve, a pivot pin spaced from and coaxial with the sleeve and supporting said guard, and extending thence towards the opposite end of the sleeve, a pivot bearing member supporting said pin for rotation and preventing its relative endwise movement, a cup supporting the pivot bearing member, and tightly received within the sleeve, and opening away from the guard, for receiving an eraser.

6. A pencil point sharpener for mechanical pencils comprising a sleeve having an internal abrasive coating at one end, a thin guard, of sheet metal or the like, disposed and formed to obstruct access to such end of the sleeve, and means for supporting said guard for rotation coaxially of the sleeve, said guard being apertured for projection of a pencil point within the sleeve and into contact with the abrasive coating, but the aperture being sufficiently small to engage and block such entrance and contact of the tip of the pencil's barrel, and the guard, at the aperture, being sufficiently thin to permit rocking the pencil to various angles of incidence to the abrasive coating, to determine the length and inclination of the point.

GEORGE D. MARTIN.
